[57] ABSTRACT

Novel intermediates useful for organic synthesis which are immonium salts of the formula

wherein R and R₁ are individually selected from the group consisting of lower alkyl, phenyl optionally substituted with halogen and benzyl and taken together are selected from the group consisting of lower alkylene, —CH₂—CH₂—O—CH₂—CH₂— and

where R₄ is alkyl of 1 to 5 carbon atoms, R₂ and R₃ are individually selected from the group consisting of hydrogen, alkyl of 1 to 5 carbon atoms and phenyl and taken together are selected from the group consisting of alkylene of 3 to 5 carbon atoms and benzoalkylene of 7 to 10 carbon atoms, X is halogen and Y is selected from the group consisting of dilower alkylamino wherein the alkyl have 1 to 5 carbon atoms, morpholino, piperidino and 1-pyrrolidinyl.

12 Claims, No Drawings

NOVEL IMMONIUM SALTS

STATE OF THE ART

French Pat. No. 1,410,864 describes certain immonium salts useful as intermediates for dyes and British Pat. No. 1,206,185 describes immonium salts useful as intermediates for pyrazoles and pyrimidines but none of the compounds of the said patents are related to the compounds of formula I.

OBJECTS OF THE INVENTION

It is an object of the invention to provide the novel immonium salts of formula I.

It is another object of the invention to provide a novel process for the preparation of the novel compounds of formula I.

It is a further object of the invention to provide novel process for the preparation of pyrazoles and pyrimidines.

These and other objects and advantages of the invention will become obvious from the following detailed description.

THE INVENTION

The novel immonium salts of the invention have the formula

wherein R and R₁ are individually selected from the group consisting of lower alkyl, phenyl optionally substituted with halogen and benzyl and taken together are selected from the group consisting of lower alkylene, $-\text{CH}_2-\text{CH}_2-\text{O}-\text{CH}_2-\text{CH}_2-$ and

where R₄ is alkyl of 1 to 5 carbon atoms, R₂ and R₃ are individually selected from the group consisting of hydrogen, alkyl of 1 to 5 carbon atoms and phenyl and taken together are selected from the group consisting of alkylene of 3 to 5 carbon atoms and benzoalkylene of 7 to 10 carbon atoms, X is halogen and Y is selected from the group consisting of dialkylamino wherein the alkyl have 1 to 5 carbon atoms, morpholino, piperidino and 1-pyrrolidinyl.

Among the preferred compounds of formula I are those wherein R and R₁ are alkyl of 1 to 5 carbon atoms such as methyl or ethyl, or phenyl substituted with a chlorine atom or taken together are alkylene of 2 to 6 carbon atoms and R₂ and R₃ are alkyl of 1 to 5 carbon atoms such as methyl, ethyl, n-propyl, isopropyl, isobu-

tyl or tert.-butyl or taken together are benzoalkylene with 1 to 4 carbon atoms in the alkylene such as

10 wherein n is 1 to 3, preferably 1 or 2, R₄ is methyl, X is bromine or chlorine and Y is dialkylamino such as dimethylamino and diethylamino.

The process of the invention for the preparation of the immonium salts of formula I comprises reacting an 15 immonium phosgene salt of the formula

wherein X, R and R₁ have the above definitions with an enamine of the formula

30 40 wherein R₂, R₃ and Y have the above definitions to obtain the corresponding immonium salt of formula I. The reaction is preferably effected in solution in an organic solvent such as methylene chloride or chloroform in substantially equimolar amounts at temperatures from 45 -50°C to 150°C , preferably 0° to 50°C and most preferably at room temperature. The compounds of formula I may be recovered by evaporation of the solvent or by precipitation such as by addition to either in which they are insoluble.

50 55 The compounds of formula II may be prepared by known processes [such as that described by Senning, Chem. Rev., Vol. 65 (1965), p. 388] by reacting a halogen X₂ with a thiocarbamoyl halide of the formula

60 65 The chlorides of N-methyl-N-benzyl-dichloromethyl immonium, N-morpholino-dichloromethyl immonium and N'-methyl-N-piperazino dichloromethyl immonium may be prepared by reacting chlorine with the corresponding thiocarbamoyl chloride in a solvent such as methylene chloride. N,N-dimethyl-dichloromethyl immonium chloride may be prepared by reacting chlo-

rine with tetramethylthiuram disulfide [Viehe et al., Angewandte Chemie., International Ed., Vol. 10 (1971), p. 573-74].

The enamines of formula III may be prepared by standard methods of producing enamines such as reacting a secondary amine of the formula YH with a carbonyl derivative of the formula

10

wherein Y , R_2 and R_3 have the above definitions.

The novel process of the invention for the preparation of pyrazoles of the formulae

IVa

and

20

25

IVb

wherein R , R_1 , R_2 and R_3 have the above definitions and R_6 is selected from the group consisting of hydrogen, alkyl of 1 to 5 carbon atoms and phenyl and isomers thereof when R_6 is other than hydrogen comprises reacting a hydrazine of the formula

VI

with a compound of formula I. Preferably, the hydrazine of formula VI or a salt thereof such as hydrochloride is added progressively to a solution of a compound of formula I in a solvent such as chloroform or methylene chloride. The compounds are preferably reacted in substantially equimolar amounts at 0° to $100^\circ C$, preferably 20° to $80^\circ C$. The pyrazole salt form can be converted into the free pyrazole by addition of a mineral base such as an aqueous solution of an alkali metal hydroxide. The pyrazole may be recovered by standard procedures such as evaporation of the solvent or by extraction and then evaporation of the solvent.

When R_6 is hydrogen, the pyrazole is a mixture of the tautomers of formulae IVa and IVb. When R_6 is other than hydrogen, the isomers of formulae IVa and IVb may be separated such as by chromatography.

The compounds of formula IVa and IVb have interesting pharmacological properties, namely analgesic and anti-inflammatory activity and therefore are useful for the treatment of afflictions characterized by inflammation such as sciatic, rheumatism, arthrosis, muscular or articular pains, toothaches and migraines. Some of these compounds have been described in British Pat. No. 1,145,544 as analgesics and anti-inflammatory agents. R is preferably methyl, ethyl, isopropyl, n-butyl or tert.-butyl in formulae IVa and IVb.

The novel process of the invention for the preparation of pyrimidines of the formula

V

wherein R , R_1 , R_2 and R_3 have the above definitions and R_7 is selected from the group consisting of hydrogen, alkyl of 1 to 5 carbon atoms and aryl of 6 to 10 carbon atoms comprises reacting an amidine of the formula

VII

with a compound of formula I.

Preferably, the reaction is effected by progressively adding the product of formula I to a solution of the amidine of formula VII in a solvent such as methylene chloride although the reaction may be effected without any solvent by heating a mixture of the 2 reactants. The reaction is preferably effected in the presence of a tertiary base such as triethylamine at 50° to $150^\circ C$. The reaction when conducted in methylene chloride is effected at reflux preferably. After completion of the reaction, the mixture is neutralized by addition of a mineral base such as an aqueous solution of sodium hydroxide or potassium hydroxide and recovering the pyrimidine in the usual fashion.

The pyrimidines of formula V have useful biological properties, particularly fungicidal activity making them useful in agriculture to combat plant diseases caused by fungi. Some of the pyrimidines of formula V have been described as fungicidal agents in French Pat. No. 1,583,150. R_7 is preferably methyl, ethyl, propyl, phenyl or naphthyl in formula V and VII.

In the following examples there are described several preferred embodiments to illustrate the invention. However, it is to be understood that the invention is not intended to be limited to the specific embodiments.

EXAMPLES 1 to 9

The compounds reported in Table I were prepared by the following procedure: The phosgene-immonium salt of formula II was suspended in methylene chloride or chloroform and then a solution of a stoichiometric amount of the enamine of formula III in methylene chloride or chloroform was added dropwise to the suspension stirred at room temperature. The stirring was continued until the phosgene immonium salt was all reacted as noted by the reaction mixture becoming a solution. About two-thirds of the solvent was evaporated and then an excess of ether was added to cause precipitation of the salt of formula I. The product was washed with pentane and then dried under reduced pressure.

9	CH ₃	CH ₃	Cl		-N-	CH ₂ Cl ₂		Cl [⊖]	404

The structures of the products of Examples 1 to 9 were confirmed by hydrolysis of the products to form the corresponding β -oxo-amides. 1 g of the product of the examples was dissolved in 100 ml of chloroform or 35

and the mixture was stirred for 15 mn. The corresponding β -oxo amide in the aqueous phase was extracted with methylene chloride or chloroform and the solvent was evaporated from the extracts. The residue was purified by distillation under reduced pressure and some of the β -oxo amides recovered are reported in Table II.

EXAMPLE 10

A solution of 0.032 moles of methylhydrazine in 50 ml of chloroform was added dropwise with stirring to a solution of 0.030 moles of the product of Example 1 in 100 ml of chloroform and the resulting mixture was refluxed (about 70°C) for 14 hours. The hydrochloric acid formed was neutralized by addition of a concentrated aqueous solution of potassium hydroxide and the mixture was extracted with chloroform. The chloroform extract was evaporated to dryness and the residue was distilled under reduced pressure to recover the product coming off at 80° to 85°C at 0.02 mm Hg. The product was a mixture of the pyrazoles of the formulae

40 The mixture consisted of 90% of isomer A and 10% of isomer B and could be separated by chromatography. RMN Spectroscopy in CDCl_3 gave the following characteristics:

Isomer A: $\delta = 1.75$ (4H.m); 2.45 (4H.m); 2.78 (6H.5); 3.55 (3H.s).

45 Isomer B: δ = 1.70 (4H.m); 2.5 (4H.m); 2.65 (6H.s);
                  3.5 (3H.s);

EXAMPLE 11

A solution of 2.33 g of hydrazine dihydrochloride in
 50 100 ml of methylene chloride was added progressively
 to a solution of 9.34 g of the compound of Example 1
 in 50 ml of methylene chloride and the mixture was
 heated at reflux for 5 hours. After cooling to 0°C, 15
 ml of an aqueous concentrated potassium hydroxide
 55 solution was added thereto. The organic phase was
 dried over potassium carbonate and the solvent was re-
 moved by evaporation. The residue was purified by dis-
 tillation to obtain a pyrazole of the formula

isomer A

isomer B

65

11

with a boiling point of 170°C at 0.04 mm Hg. This RMN Spectrum was as follows: $\delta = 9.3$ (1H,br); 2.85 (6H,s); 2.6-1.4 (8H).

EXAMPLE 12

Using the procedure of Example 11, phenyl hydrazine was reacted with the product of Example 1 to obtain a mixture of pyrazole of the formulae

and

EXAMPLE 13

1.04 g of benzamidine and 2.5 ml of triethylamine were introduced into 100 ml of methylene chloride and then a solution of 2.7 g of the compound of Example 1 in 50 ml of methylene chloride was added dropwise thereto. The mixture was refluxed with stirring for 24 hours and was then neutralized with a potassium hydroxide solution. The aqueous phase was saturated with potassium carbonate and then was extracted with methylene chloride. The methylene chloride was eliminated by evaporation from the extract and the residue was distilled under reduced pressure to obtain the pyrimidine of the formula

distilling at 150°C at 0.3 mm Hg. The product was purified by crystallization from a 1:1 water-methanol mixture. The product had a melting point of 88°C; a mass spectra: 253 (M^+); and an IR spectrum $\gamma = 2940, 2860, 1590, 1550$ and 1400 cm^{-1} .

EXAMPLE 14

Using the procedure of Example 13, 0.7 g of the product of Example 5 was reacted with 0.52 g of benzamidine and 1.5 ml of triethylamine to obtain the pyrimidine of the formula

12

distilling at 160°C at 0.04 mm Hg. The product was purified by crystallization from benzene. The product had a mass spectra of 301 (M^+) and IR spectrum $\gamma = 2940, 2860, 1600$ and 1550 cm^{-1} .

5 Various modification of the products and processes of the invention may be made without departing from the spirit or scope thereof and it should be understood that the invention is to be limited only as defined in the appended claims.

10 We claim:

1. Immonium salts of the formula

25 wherein R and R1 are individually selected from the group consisting of lower alkyl, phenyl optionally substituted with halogen and benzyl and taken together are selected from the group consisting of lower alkylene, $-\text{CH}_2-\text{CH}_2-\text{O}-\text{CH}_2-\text{CH}_2-$ and

30

35 where R4 is alkyl of 1 to 5 carbon atoms, R2 and R3 are individually selected from the group consisting of hydrogen, alkyl of 1 to 5 carbon atoms and phenyl and taken together are selected from the group consisting of alkylene of 3 to 5 carbon atoms and benzoalkylene of 7 to 10 carbon atoms, X is halogen and Y is selected from the group consisting of dilower alkylamino wherein the alkyl have 1 to 5 carbon atoms, morpholino, piperidino and 1-pyrrolidinyl.

40 2. The compounds of claim 1 wherein X is chlorine.

45 3. A compound of claim 2 wherein R and R1 are methyl, R2 and R3 together are $-(\text{CH}_2)_4-$ and Y is 1-pyrrolidinyl.

4. A compound of claim 2 wherein R and R1 together are

50 R2 and R3 together are $-(\text{CH}_2)_4-$ and Y is 1-pyrrolidinyl.

55 5. A compound of claim 2 wherein R and R1 are methyl, R2 and R3 together are $-(\text{CH}_2)_3-$ and Y is 1-pyrrolidinyl.

60 6. A compound of claim 2 wherein R is benzyl, R1 is methyl, R2 and R3 together are $-(\text{CH}_2)_3-$ and Y is 1-pyrrolidinyl.

65 7. A compound of claim 2 wherein R and R1 are methyl, R2 and R3 together are

and Y is 1-pyrrolidinyl.

8. A compound of claim 2 wherein R and R₁ are methyl, R₂ is phenyl, R₃ is hydrogen and Y is 1-pyrrolidinyl.

9. A compound of claim 2 wherein R and R₁ together are -(CH₂)₂-O-(CH₂)₂-, R₂ and R₃ together are -(CH₂)₄- and Y is morpholino.

10. A compound of claim 2 wherein R and R₁ are methyl, R₂ is hydrogen, R₃ is tert.-butyl and Y is di-methylamino.

11. A compound of claim 2 wherein R and R₁ are methyl, R₂ and R₃ together are

and Y is 1-pyrrolidinyl.

12. A process for the preparation of a compound of claim 1 comprising reacting a phosgene-immonium salt of the formula

wherein R, R₁ and X have the definitions of claim 1 with an enamine of the formula

wherein R₂, R₃ and Y have the definitions of claim 1 to obtain the corresponding immonium salt of claim 1.
